UNITED STATES PATENT OFFICE.

ANTONIO CERRUTI, OF SAN FRANCISCO, CALIFORNIA.

SYRUPING-MACHINE.

1,154,374.

Specification of Letters Patent. Patented Sept. 21, 1915.

Application filed October 10, 1911. Serial No. 653,858.

To all whom it may concern:

Be it known that I, ANTONIO CERRUTI, citizen of the United States, residing in the city and county of San Francisco and State of California, have invented new and useful 5 Improvements in Syruping-Machines, of which the following is a specification.

This invention relates to a machine for filling cans and other receptacles with liquids, such as syrup, and particularly pertains to an apparatus for syruping cans in which the fruit, or other material to be canned, has been previously packed.

The special object of this invention is to 15 provide a valveless, sanitary, economically operated, syruping machine, by means of which cans may be automatically filled with the desired syrup, or other liquid, to a predetermined point which is a short distance 20 below the top of the can, irrespective of the quantity or volume of the solids contained in the can.

A further object is to provide an automatic can filler which is so constructed and 25 arranged as to prevent waste of the syrup, and to obviate overflowing of the can; thereby doing away with the necessity of having to wash the syruped cans prior to capping or sealing, as commonly required in can-filling 30 machines, now generally in use.

Another object is to provide an automatic, continuously operated machine of large capacity, and which is adaptable to the handling of various liquids and the regulation 35 of the quantity of liquids, etc., delivered to the cans.

Other objects of this invention, together with the advantages to be derived from its use, will be made apparent in the following 40 specification.

The invention consists of the parts and the construction and combination of parts as hereinafter more fully described and claimed having reference to the accompanying 45 drawings, in which—

Figure 1 is a plan view of a can filling machine, with parts broken away, constructed in accordance with the invention. Figs. 2—3—4 are detail vertical sections of the 50 can filling apparatus, showing it in the various positions assumed in the filling operation. Fig. 5 is a plan view of same in the position shown in Fig. 2. Figs. 6 and 7 are diagrams of the circular cam tracks employed in operating the filling apparatus.

In the drawings, A represents a revoluble

tank for containing the liquid to be delivered to the cans, which tank is designed to be rotated continuously in any suitable manner. It is here shown as supported on 60 a vertically disposed shaft 2, which is rotated continuously through a worm wheel 3, and a worm 4 from a drive shaft 5 driven by any suitable source of power. Rigidly mounted on, or formed integral with the 65 outer face of the perpendicular wall of the tank A is a series of radially disposed horizontally extending brackets 6, each of which carries a vertically arranged rocker-arm 7, which is pivotally mounted thereon at 8. 70

The lower end of each rocker-arm 7 has a horizontally disposed can supporting plate or table 9 formed thereon and mounted on a hub 10 formed on the underside of the plate 9 is a roller or wheel 11. The wheel 11 is 75 designed to travel on a circular cam track 12 when the tank A is rotated; the track 12 having an undulating surface to cause the rocker-arm 7 to rock on its pivot 8, as will be later described, and thereby move the can 80 supporting plate 9 into various positions in relation to a horizontal plane.

Pivottally mounted at 13 on the upper end of the rocker-arm 7 is an arm 14 on the outer end of which is carried a peculiarly 85 constructed cap which is designed to form a temporary closure for the can to be filled and also acts as a nozzle to direct liquids from the tank A to and from the can as will be later described. This cap is shown as consisting of a hollow horizontally disposed member 15, on which a downwardly extending annular flange 16 is formed, this flange 16 being designed to surround the upper edge of a can B, supported on the plate 9 as 90 shown in Figs. 2—3 and 4. The cap member 15 has an opening on its underside within the flange 16, over which opening is placed a perforated plate 17; the plate 17 being rigidly held in place by means of a bolt 18 95 103 which is inserted through the top of the cap member 15. The upper face of the perforated plate 17 is flush with the lower inside face of the cap member 15, and its lower face extends sufficiently far beneath the underside of the member 15 to form an annular groove between the outer periphery of the disk 17 and the inner periphery of the flange 16; the disk 17 being of such diameter as to extend into the end of the can B, as 110 shown in Figs. 2—3 and 4.

A gasket 17', or ring of rubber, or other

2

suitable material is disposed in the groove formed between the disk 17 and flange 16, and is adapted to contact the upper edge of the can B, so as to form a tight joint 5 or seal and prevent the escape of the liquid when the can is being filled.

Formed on the rear of the cap 15 is a downwardly extending tubular portion, or syrup duct 19, the upper end of which opens to the interior of the cap. A flexible hose 20 is attached to the lower end of the tube 19 and leads therefrom to the tank A, so as to form a communication between the interior of the hollow cap 15 and the tank, 15 to admit of the free passage of the liquid in the tank to and from the interior of the cap 15. A vent pipe 21 leads from the cap 15 to permit of the escape of the air displaced by the liquids entering the cap 15 20 and can B, when the latter is being filled.

Means as follows, are provided for automatically closing the cap upon the can to be filled, and for clamping it securely in the closed position, so as to rigidly hold the
25 can against movement. 22 is a rod which is slidably mounted in a laterally extending bracket 23, formed on the lower portion of the rocking arm 7, and which rod is attached at its upper end to the arm 14 at a
30 point adjacent the cap 15; the rod 22 passing through an elongated perforation in the arm 14. A pin 24, inserted in a perforation in the rod 22, adjacent the under side of the arm 14, acts as a support for the latter to
35 cause it to move upward when the rod 22 is moved upwardly, as will be presently described; a nut 25 being screwed on the upper end of the rod 22 above the arm 14 to insure the latter moving downwardly
40 with the rod.

The rod 22 is reciprocated by means of a lever arm 26 which is pivotally mounted at its upper end on the rocker arm 7 and is connected to the lower end of the rod 22 by means of a toggle link 27; one end of the link being pivoted to the rod 22 and the other end pivoted to the lever arm 26 at a point midway between its connection with the rod 22 and the pivotal mounting of the lever arm 26. The lower end of the lever arm 26 carries a roller 28 which is adapted to travel over the upper and lower faces of a circular cam track 29 when the tank A and its connections are rotated; the cam track 29 being so shaped that the lever arm 26 will be caused to rock in such manner as to move the rod 22 and thereby actuate the cap member 15.

60 The tank A is designed to be filled automatically from any suitable source of supply through a pipe 30, in which is disposed a cut-off valve 31, of any suitable construction which valve is adapted to be operated by means of a float 32 in such manner as 65 to regulate the flow of liquids to the tank.

A and maintain the liquid at a normally uniform level in the tank.

In operation of the invention, the tank A, with its connections is rotated by means of the worm 4 and worm-wheel 3, as before mentioned, causing the rollers 11 and 28 to travel upon the circular cam-tracks 12 and 29, respectively. The cans B to be filled, are delivered successively to the can supporting plates 9 at a point indicated at *a*, in Fig. 1, by any suitable can feeding mechanism. This mechanism is here shown as consisting of a star-wheel 33, which is adapted to engage cans delivered thereto on an endless belt or conveyer 34, and carry them on to the plates 9 in the manner commonly employed in canning machinery.

A can B on passing onto a plate 9, at *a*, is carried forward by the latter against a stationary resilient tongue or plate spring 35, which acts to shove the can between guide flanges 36 carried by the rocker arm 7. The flanges 36 serve to insure the can B being positioned directly beneath the cap member 15, which at the point marked *a* Fig. 1, is in the elevated position indicated by dotted lines in Fig. 2, which position of the cap member 15 admits of the can B being placed thereunder, as just described. The cap member 15 is supported in this elevated position by means of the lever arm 26, the lower end of which is supported upon the upper face of a section of the cam track 29, as indicated at *b* in Fig. 7; the lever arm 26 acting on the cap 15 through the rod 22 and pin 24, as before mentioned. The roller 28 on the lever arm 26 moving forward after the can B has been positioned on the plate 9, as indicated at *c* in Fig. 1, is caused to pass beneath a section of the cam track 29, as indicated at *d* in Fig. 7 so as to travel on the underside thereof; the cam track being so shaped at this point as to cause the lever arm 26 to move downwardly and thereby act on the cap member 15 through the rod 22 and toggle-link 27 in such manner as to clamp the cap member 15 securely against the upper end of the

19 secures, against the upper edge of the can as shown in Fig. 2; the gasket 17' bearing tightly against the upper edge of the can to form a tight seal at this point. Sufficient space is provided between the pin 24 and nut 25 on the rod 22 to allow of the free rocking movement of the arm 14, the slot in the arm through which the rod passes being elongated to admit of the arm moving in an arc of a circle when the rod moves vertically. 115 120

The lever arm 26 in moving downward carries the upper end of the toggle link 27 beyond the vertical center of the rod 22, as indicated at *z* in dotted lines in Fig. 2, thereby locking the cap 15 in a fixed position. 125

The moment the can B has been closed by the cap 15, the roller 11 carried by the plate 130

9 on the rocker-arm 7 passes down an inclined portion of the cam track 12 onto a lower level portion thereof as indicated at *e* in Figs. 3 and 6, which action causes the rocker arm 7 to tilt outwardly on its pivot 8 so as to cause the mouth of the can B and the hollow cap 15 together with the outlet end of the valveless duct 20 to assume a position below the normal level of the liquid contained in the tank A, as particularly shown in Fig. 3. This causes liquid to flow from the tank A, through the flexible hose 20 into the hollow cap 15 and thence through the perforated disk 17 into the interior of the can B; the air displaced by the liquid entering the cap and the can, escaping through the vent 21. The section *e* of the circular cam track 12 is of such length as to retain the can B below the normal level of the liquid in the tank A a sufficient length of time to insure the can being completely filled as it is carried forward, whereupon the roller 11 passes up an inclined portion of the cam track 12 onto an elevated portion thereof, as indicated at *f* in Figs. 4 and 6. The portion *f* of the cam track 12 is disposed at such distance above the portion *e* that the mouth of the can B and the outlets in cap 15 will be elevated to a point above the normal level of the liquid contained in the tank A, as shown in Fig. 4; the upper end of the can being tilted toward the tank by reason of its being carried on the rocker arm 7 and moving therewith as the latter is rocked on its pivot 8.

It will be seen that by disposing the can B with its mouth above the normal level of the liquid in the tank A and tilting it toward the tank, as shown in Fig. 4, that the liquid contained in the cap 15, together with a portion of that in the can B will flow back through the tube 19 and be returned to the tank A through the hose 20, so that when the can is again returned to the perpendicular, or upright position shown in Fig. 2, the level of the liquid therein will be below the upper edge of the can and the lower face of the perforated plate 17. The can B is restored to the perpendicular position by the wheel 11 traveling down an inclined portion of the cam track 12 onto a level portion thereof indicated at *g* in Fig. 6, which portion is disposed on a plane between the portions *e* and *f*, and is that portion of the cam track on which the roller 11 is supported when the can B is fed to the plate 9 at *a*.

The moment the can B is restored to the vertical position, or shortly thereafter, the roller 28 on the lever arm 26 passes back to the upper side of the portion *b* of the cam track 29, which acts to rock the lever arm 26 upwardly, so as to lift the cap 15 from the can B back to the position shown in dotted lines in Fig. 2. The can B is then automatically removed from the plate 9, at a

point indicated at *h* in Fig. 1, by means of a star wheel 36', or any equivalent means which will prevent splash of the contents of the can, which latter is delivered to an endless belt or conveyer 37^a to be afterward fed to a can capping machine of any suitable construction. 70

The cycle of operation may be briefly summarized as follows: In Fig. 2 the empty can is shown clamped in position and at the time the can support is traveling around the track section shown in Fig. 7 between *b* and *d*, the roller 28 already having passed over section *b*. 75

In Fig. 3 roller 11 has passed into the depressed section *e* of Fig. 6 and roller 28 is under the lowest depressed section *d* Fig. 7; the hollow cap 15 being clamped down on top of the can and the hollow chamber in the cap below the liquid level in tank A. In 80 this position the can is flooded. 85

Fig. 4 shows the can support moving on until roller 11 is on the elevated track section *f*, Fig. 6, and roller 28 is still traveling along the under-side and adjacent to the terminus of the more elevated portion of section *d*, Fig. 7. In this position the mouth of the can is above the level of the liquid in tank A and the surplus is draining back into the tank. As the can support continues its rotary movement roller 11 drops again on to the track section *g*, Fig. 6, and the roller 28 runs on top of the track section *b* on the right of Fig. 7, leaving the filled can standing upright with the cap lifted and the parts in the position indicated in Fig. 2. On a filled can being removed, the foregoing cycle of operation is repeated. 90 95 100

From the foregoing it will be seen that I have provided a can filling machine which is simple in construction and continuous in its operation; the empty cans being fed successively to the constantly moving can supporting plates 9 at the point *a*, as shown in Fig. 1, and are filled during the time occupied in traversing to the point of discharge *h*. It will also be observed that by employing the method and means herein disclosed for filling the can, each can will be filled with the liquid to a given and uniform point below its upper edge, which point is governed by the extent of the tilt given the can after filling, as shown in Fig. 4, which in turn is controlled by the height of the portion *f* of the cam track 12. By varying the height of the portion *f*, the quantity of liquid left in the cans may be regulated. This tilting of the can so that its mouth is above the normal level of the liquid contained in the tank A to drain off the excess constitutes an important feature of this invention for the reason that it insures the can being filled with liquid to a certain uniform level, irrespective of the quantity or volume of solids contained in the can. 110 115 120 125 130

By providing a tight seal between the can and the cap 15, the prevention of overflow of the liquids around the exterior of the can is insured, thereby keeping the exterior of 5 the can in a clean condition and rendering it unnecessary to subject the can to washing operations before delivering it to capping and labeling machines, as is now generally required.

10 In event a can B is not positioned on the can supporting plate 9, means are provided for preventing the downward tilt of a rocker-arm 7, so that the cap 15 will be maintained above the level of the liquid in 15 the tank A and thereby prevent the spilling and waste of the liquid when there is no can in position to receive it. These means are here shown as consisting of an auxiliary section of the cam track 12, which is indicated at 37, in Figs. 1 and 6. This auxiliary section 37 is disposed above the depressed portion e on a level with the portion g, and is connected with the latter by means of a horizontally swinging section 38, pivoted at 25 38' on the end of the section 37. The swinging section 38 is normally closed to bridge the gap between the sections g and 37, and is retained in the closed position by means of a spring 39. The opposite end of the 30 auxiliary section 37 terminates a short distance from the incline leading to the section f, and a vertically swinging section 40, hinged on the section 37 bridges the gap therebetween and is normally disposed in 35 its closed position by gravity.

In the event no can is delivered to the plate 9, the roller 11 will travel across the sections 38-37 and 40 so as to maintain the plate 9 in its level position, but when a can 40 is in position on the plate 9 it will contact the end of a lever 41 which extends in the path of travel of the can; the lever 41 being rocked on its pivot 42 as the can moves ahead. The lever 41 being connected to an 45 arm on the section 38 by means of a rod 43, the section 38 will be caused to rock outwardly as the inner end of the lever 41 is advanced with the can, so as to allow the roller 11 to pass downwardly beneath the 50 auxiliary section 37 onto the section e, thereby tilting the can, as before described. The roller 11 on passing up the inclined portion of the track 12 between the sections e and f lifts the hinged section 40, which drops back 55 to its normally closed position when the roller 11 has passed, the swinging section 38 also returning to normal the moment the can frees the lever 41. The length of the section e of the track 12 may be adjusted if 60 desired, so as to regulate the time in which the can will be retained below the liquid level, and thereby insure the can being filled.

65 It is manifest that while I have shown the invention as employed in filling cans, such

as are used in canning fruits and vegetables for market, and for convenience I term the invention a syruping machine, it is equally applicable for use in filling other receptacles with any liquid; the general operation 70 of the apparatus remaining substantially the same in all instances, while the detailed construction of the cap or nozzle is subject to slight variations, according to the size and style of the receptacle to be filled. 75

The cam track construction here shown is also subject to various modifications, as is the can feeding and discharging mechanism, the essential feature being to provide a cap or closure for a receptacle which opens to 80 the interior of the receptacle and is connected with a source of liquid supply and to provide means for positioning the receptacle with its mouth below the source of liquid supply to allow the liquid to gravitate into 85 the receptacle, then to elevate the receptacle so as to pour a surplus of the liquid back to the source of supply and thereby insure the liquid in the receptacle filling the latter to a predetermined point. It is to be observed 90 that the can is thus filled through the tilting of the can about a center, which is external to the can.

By this construction here shown, the use 95 of weighing and measuring devices are dispensed with; valves for controlling the flow of liquid to the receptacle also being done away with, thus producing a machine which is positive in its operation, accurate, sanitary, and efficient, and not liable to get out 100 of order, and capable of a large output.

Having thus described my invention, what I claim and desire to secure by Letters Patent is—

1. A can syruping machine, consisting of 105 a can support turning about a vertical axis, having means for holding an open top can, and means for tilting the support toward and from its vertical axis and means for syruping the can operated by the tilting of 110 the can.

2. A can syruping machine, consisting of means for supporting and for moving a can continuously, means for tilting the can, and means for syruping the can operated by the 115 tilting of the can.

3. A can syruping machine, consisting of means for supporting and for moving a can continuously, means for tilting the can, and means for syruping the can operated by the 120 tilting of the can about a center external to the same.

4. A syruping machine, consisting of means for supporting and moving a can continuously, means operated by the can supporting means for tilting the can, and means for syruping the can, first by tilting the can in one direction and then tilting it in the opposite direction. 125

5. A can syruping machine, consisting of 130

- means for supporting and closing the mouth of the can, means operated by the can supporting means for tilting the can, and means for syruping the can, including valveless appliances operated by first tilting the can in one direction and then tilting it in the opposite direction and then righting the can.
6. A syruping machine, consisting of means for supporting and moving continuously a can to be syruped, means to tilt the can supporting means, a source of liquid supply and valveless fluid connections with said source of supply controlled by the tilting of the can.
7. A syruping machine consisting of means for supporting and moving a can to be syruped, means to tilt the can supporting means, a source of liquid supply and valveless fluid connections with said source of supply controlled by the tilting of the can.
8. A syruping machine consisting of means for supporting and moving continuously a can to be syruped, means to tilt the can supporting means, a source of liquid supply and fluid connections with said source of supply controlled by the tilting of the can.
9. In a can filling machine, a tank, a valveless conduit leading therefrom, a nozzle on the outer end of said conduit, means for clamping said nozzle on a can to be filled, and means for successively disposing the nozzle when the latter is clamped on the top of the can first below then above the level of a liquid in the tank.
10. In a can filling machine, the combination with a tank of a rocking can support, a hollow cap for the top of the can carried by said support, fluid connections between the hollow cap and the tank, and means to rock the support so as to dispose the cap and the open end of the can first below then above the level of a liquid in the tank to fill the can.
11. A can filling machine, comprising a support for a can, a hollow cap engageable with and opening to a can on said support, a tank, means for conveying liquid from the tank to the cap, means for rocking the can support to cause liquid to flow therein from the tank, and means for tilting the can to pour a portion of the liquid therein back into the tank.
12. In a can filling machine, a hollow closure for the can opening to the interior thereof, a reservoir for liquids, means for connecting the reservoir with the can closure for conducting the liquid to the interior of the can, and means for successively lowering the upper end of the can below the level of the liquid in the reservoir to fill the can, and elevating the can at an angle above the liquid in the reservoir to partly empty the can.
13. A can filling machine, comprising a rotatable tank, can supporting means pivotally mounted on said tank, a hollow cap for engaging and closing a can on said support, a conduit connecting the cap and tank, and means whereby the can supporting means will be rocked to alternately dispose the upper end of the can thereon first below then above the level of the liquid in the tank.
14. A can filling machine comprising a revoluble tank, a rocker arm mounted on said tank, a can supporting plate carried on said rocker arm, means for actuating said rocker arm to dispose the upper end of a can carried by said plate first below then above the level of a liquid in said tank, and means by which liquid will be delivered to the can from the tank when the can is in its lowermost position and which will admit of a portion of the liquid in the can being returned to the tank when the can is in its uppermost position.
15. A can filling machine comprising a revoluble tank, a rocker arm mounted on said tank, a can supporting plate carried on said rocker arm, means for actuating said rocker arm to dispose the upper end of a can carried by said plate first below then above the level of a liquid in said tank, said means consisting of a circular cam track positioned to rock the rocker arm as the tank revolves, and means by which liquid will be delivered to the can from the tank when the can is in its lowermost position and which will admit of a portion of the liquid in the can being returned to the tank when the can is in its uppermost position.
16. A can filling machine comprising a rotary tank, a rocker arm pivotally mounted on said tank, a circular cam track adapted to actuate the rocker arm, a plate for supporting a can carried by the rocker arm, a cap pivotally mounted on said arm and arranged to engage the upper end of a can on said plate, and means carried by said cap connected with the tank for delivering liquid to the interior of the can.
17. A can filling machine comprising a rotary tank, a rocker arm pivotally mounted on said tank, a circular cam track adapted to actuate the rocker arm, a plate for supporting a can carried by the rocker arm, a cap pivotally mounted on said arm and arranged to engage the upper end of a can on said plate, automatic means for clamping said cap upon the can, and means carried by said cap connected with the tank for delivering liquid to the interior of the can.
18. In a can filling machine, a revoluble tank, a plurality of can supporting members pivotally connected to said tank to swing about a horizontal axis, means for establishing communication between the interior of a can on each of said members and the tank, means by which the rotation of said tank will cause the can supporting mem-

- bers to rock to dispose the upper ends of cans successively first below then above the level of the liquid in the tank, so as to first fill the can then partially empty it.
- 5 19. In a can filling machine, a revoluble tank, a series of rockable can supporting members carried by said tank, means for automatically delivering cans successively to said can supporting members, means for 10 clamping the cans against movement on said members, means carried by said can clamping means for delivering liquid to the can from the tank, and means controlled by the cans by which the supporting members 15 are rocked downwardly to cause a filling charge to enter the can.
20. In a can filling machine, a revoluble tank, a series of rockable can supporting members carried by said tank, means for 20 automatically delivering cans successively to said can supporting members, means for clamping the cans against movement on said members, means carried by said can clamping means for delivering liquid to the can 25 from the tank, and means controlled by the cans by which the supporting members are rocked downwardly to cause a filling charge 30 to enter the can, including means for elevating the can supporting members to discharge a portion of the liquid back into the tank.
21. In a can filling machine, a rockable can supporting plate, a circular cam track on which the free end of the plate is supported, 35 means for causing the plate to traverse the cam track, means for clamping a can on said plate, including a hollow cap member arranged to close a can disposed on said plate, said cap opening to the interior of the 40 can, and means for filling the can through said cap controlled by the action of the cam track.
22. In a can filling machine, a tank, means 45 for automatically delivering a liquid to said tank and maintaining a uniform depth of liquid therein, a nozzle adapted to close the upper end of a can, an unobstructed conduit leading from the tank to the nozzle and means for supporting a can beneath said 50 nozzle, said means adapted to be rocked downwardly for lowering the can to allow liquid to flow from the tank into the can and to be rocked upwardly to allow a portion of the liquid to be emptied back into the 55 tank so as to fill the can to within a certain distance of its upper end.
23. The combination of a tank, means for 60 maintaining therein a constant level of liquid, a valveless duct connected with the tank, a can support, means for bringing the outlet end of the duct below the level of the liquid in the tank when a can is in position to be filled, and means for elevating the outlet end of the duct above the level of the 65 liquid in the tank and tilting the can toward the outlet end so as to discharge the surplus liquid back into the tank.
24. A continuously operating can syruper 70 consisting of a rotary support, a series of radially arranged tilttable syruping ducts, each having a perforated cap to fit over the mouth of a can, can supporting means traveling with the ducts, and means by which the cans are automatically syruped by the 75 tilting movements of the ducts.
25. The combination with a can carrier, means for flooding the can with syrup by gravity by tilting the can in one direction, means for tilting the can in the opposite direction to pour off part of the liquid contents, and means for holding in the solids 80 in the can during the syruping operations.
26. The combination with a can carrier, means for flooding the can with syrup by gravity by tilting the can in one direction, means for tilting the can in the opposite direction to pour off part of the liquid contents, and means for holding in the solids 85 in the can during the syruping operations.
27. In a filling machine, horizontally rotary supporting apparatus, in combination with a multiplicity of receptacle fillers mounted on said supporting apparatus so as to be reclinable; means to place said receptacle fillers alternately into reclining and into erect position; and means to fill the receptacles while said receptacle fillers are resting in reclined position; substantially as 90 described.
28. In a filling machine, a tank, a conduit leading therefrom, a traveling receptacle support, a nozzle on the conduit, means for automatically clamping said nozzle on the top of the traveling receptacle, and means whereby the top of the receptacle and nozzle will be successively disposed below and 95 above the level of the liquid in the tank to fill the receptacle with liquid from the tank.
29. A can syruping machine consisting 100 of a can support turning about a vertical axis, having means for holding an open top can, means for lowering the support, and means for syruping the can brought into operative position by lowering the can support.
30. In a filling machine, horizontally rotary supporting apparatus, in combination with a multiplicity of receptacle fillers mounted on said supporting apparatus so as to be reclinable in vertical planes substantially coincident with the vertical axis of the supporting apparatus, means to place said receptacle fillers alternately into reclining and into erect position, and means to fill said receptacles while resting in reclined position, substantially as described.
31. In a filling machine, horizontally rotary supporting apparatus, in combination 110 with a multiplicity of receptacle carriers 115
- 120
- 125
- 130

mounted on said apparatus, means to place said carriers, and receptacles carried by them, during a given period in the travel of said supporting apparatus automatically 5 into reclined position, and during another such period automatically into erect position, and automatic means to fill said receptacles in reclined position.

32. In a filling machine, horizontally rotatory supporting apparatus, carrying a multiplicity of filling nozzles and a multiplicity of receptacle carriers adapted to hold receptacles in reclined position, means for automatically bringing said filling nozzles into 10 engagement with receptacles supported by said carriers, means for automatically disengaging such nozzles from such receptacles, and automatic means to convey fluid into said receptacles through said nozzles while 15

said receptacles are being held in reclined 20 position.

33. In a filling machine, a fluid tank, a conduit leading therefrom, a nozzle on the conduit, a traveling receptacle support, means for automatically clamping said nozzle on the top of a receptacle carried by said support, and means whereby the top of the fluid channel through said conduit and nozzle may be successively disposed below and above the level of the liquid in the tank. 25

In testimony whereof I have hereunto set my hand in the presence of two subscribing witnesses.

ANTONIO CERRUTI.

Witnesses:

JOHN H. HERRING,
CHARLES EDELMAN.
